His Attorney.

UNITED STATES PATENT OFFICE.

JOSEPH W. GOSLING, OF SCHENECTADY, NEW YORK, ASSIGNOR TO GENERAL ELECTRIC COMPANY, A CORPORATION OF NEW YORK.

DESIGN FOR A LAMP-GLOBE.

• 50,192.

Specification for Design.

Patented Jan. 16, 1917.

Application filed November 4, 1916. Serial No. 129,620. Term of patent 14 years.

To all whom it may concern:

Be it known that I, JOSEPH W. GOSLING, a citizen of the United States, residing in Schenectady, county of Schenectady, State of New York, have invented a new, original, and ornamental Design for Lamp-Globes, of which the following is a specification.

The accompanying drawing is a perspective view of my ornamental lamp globe,

which is formed of light transmitting or translucent material.

I claim—

The ornamental design for a lamp globe as shown and described.

In witness whereof, I have hereunto set my hand this 3rd day of November, 1916.

JOSEPH W. GOSLING.
